PUSH-BUTTON STEPPING SWITCH

Harold C. Macnamara, Minneapolis, Minn.

Application December 20, 1946, Serial No. 717,559

3 Claims. (Cl. 200—156)

1

This invention relates to improvements in push-button electrical switches of the type which is operated to both its "off" and "on" position by means of a single reciprocable pushbutton, the primary object of the invention being to provide a simplified, electrically more efficient, and more easily manufactured switch of this type.

Other important objects and advantages of my invention will be apparent from the following description and the drawings appended thereto, wherein for illustration only, an exemplary embodiment of my invention is set forth in detail.

In the drawings:

Figure 1 is an elevation of the outer end of a switch constructed in accordance with this invention, showing the same installed in a wall and with the cover plate removed.

Figure 2 is a vertical longitudinal section taken through Figure 1 along the line 2—2, and showing the mechanism in initial or retracted position.

Figure 3 is a horizontal section taken along the line 3—3 of Figure 2.

Figure 4 is a fragmentary sectional detail on an enlarged scale, taken along the line 4—4 of Figure 3.

Figure 5 is an enlarged section taken on the line 5—5 of Figure 3, showing arms of the contactor in full lines engaged with the two contacts of the switch in the "on" position thereof, and showing the contactor arms in dotted lines disengaged from said contacts in the "off" position of the switch.

Figure 6 is an end elevation of the contactor as shown in Figure 5.

Figure 7 is an enlarged sectional detail of the pawl structure, taken along the line 7—1 of Figure 3.

Figure 8 is an enlarged sectional detail of one of the switch contacts, taken along the line 8—8 of Figure 3, and

Figure 9 is a transverse section taken on the line 9—9 of Figure 3.

The example herein chosen to illustrate the present invention is a flush-type wall switch generally designated 10, comprising the preferably metal cylindrical casing 11 having upper and lower ears 12 and 13, respectively, on its outer end which are traversed by screws or the like 14 entering the wall lath 15 or the equivalent for mounting the switch in place on the wall 16. Screws 17 hold in place on the outer end of the casing 11, the vertical support strip 18, which has an enlarged annular middle portion 19 encircling and supporting the pushbutton 20 which extends reciprocably therethrough.

2

The cover plate 21, which covers the outer end of the casing 11 and the support strip 18, has a flange 22 to engage the wall 16 around the casing and laterally outwardly of the ears 12 and 13, as shown in Figure 2. The cover plate is held removably in place by means of two diametrically opposed triangular shaped tongues 23, 23 which enter the outward end of the casing 11 at opposite sides of the ring 18 of the support strip 18, as shown in Figure 3, and have notches 24 in their outer straight edges arranged to securably engage lateral projections or lugs 25 on the free ends of laterally inwardly tensioned leaf springs 26 which have their opposite ends, in this instance their inward ends, riveted or otherwise secured to the sidewall of the casing 11, as indicated at 27. The flat tongues 23, 23 engage through guide slots 28 provided in the insulating material switch body 29, whereby the tongues are accurately guided into place and whereby with the tongues 23 engaged with the springs 26, the wall or cover plate 21 is securely held in proper position, when installed, and can be quickly and easily removed when desired by drawing it outwardly so as to disengage the tongues 23, 23 from engagement with the projections 25 of the springs 26.

The open outer end of the insulated material generally cylindrical switch body 29 is supportably secured in a suitable manner to the support strip 18 and extends rearwardly within and is concentrically spaced from the sides of the casing 11, and spaced from its closed inward end 29. The switch body 29 is composed of two similar semi-circular sections 30, 31 separably secured together, as shown in Figure 9, by a long bolt 32 traversing the sections through shank recesses 33 located at one side of the rear or inward part of the switch body 29 and by a short bolt 34 passing through shank recesses 35 at the opposite side of the rear or inward end of the switch body.

The outer or forward end of the switch body 29 is formed with an axial bore 36 for accommodating the cylindrical reciprocable pushbutton 20, this bore being long enough to permit the necessary inward movement of the pushbutton from the initial or rest position shown in Figures 2 and 3 to operative position. The bore 36 has an enlargement 37 accommodating a stop flange 38 formed on the pushbutton intermediate its ends. A helical expanding spring 39 is circumposed on the pushbutton between the stop flange 38 and the inner end of the bore enlargement 37, so that the pushbutton will normally be pressed outwardly in its rest or ready position.

55 The inner end of the bore 36 opens into a

relatively narrow, vertically elongated, substantially rectangular chamber 40, one wall of which is formed with a socket 41 in which is rotatably confined a relatively large diameter stubshaft 42 having circumferentially spaced indentations 43 thereon for engagement by a spring-pressed ball detent 44 set in a radial socket 44 leading from the wall of the socket 41, whereby the ratchet wheel 45 which is attached to or integral with the stubshaft 42 will be held in certain positions of rotation as hereinafter described.

A smaller diameter stubshaft 46 on the opposite side of the ratchet wheel 45 is rotatably confined in a socket 47 provided in the opposite wall of the chamber 40, substantially midway between the diametrically aligned rounded heads 48, 49 of two contacts 49, which project through the switch body 29.

As shown in Figure 8, the shanks of the contacts 49 are formed with axial threaded bores 50 receiving binding post screws 51 having wide flat heads 52 for forcibly confining thereunder and in the cups 53 on the adjacent ends of the contacts 49, the wires 54 which are thereby electrically connected to the switch 10.

The contact heads 48 extend sufficiently from the wall of the chamber 40 to be fully contacted by the arms 55 of the cruciform contactor 56 which is secured by screws or the like 57 to the adjacent side of a dielectric or insulated disk 58 forming a part of the ratchet wheel 45 and fixed to turn therewith. The contactor arms 55, as indicated in Figure 5, are so disposed and proportioned that any two diametrically aligned arms can be engaged with and electrically bridge the contact heads 48 or be disengaged from the contact heads and positioned therebetween, as shown in full and dotted lines in Figure 5.

The pushbutton 20 is equipped with the pawl 59 for operatively engaging the teeth 60 of the ratchet wheel, in such a way that each time the pushbutton is pushed inwardly and released to be returned to its initial or rest position by the spring 39, the ratchet wheel is turned toward the right or clockwise in Figure 2, a distance of one tooth or one-eighth of a revolution, enough in the situation shown in Figure 5, to remove the contactor arms engaged with the contact heads 48 to the position shown in dotted lines, corresponding to one of the "off" positions of the switch. The following in-pushing of the pushbutton will cause the next adjacent contactor arms to engage the contact heads 48, and the next such actuation will disengage them from the contact heads. In this way successive pushing in of the pushbutton 20 and release thereof will produce alternately the "on" and "off" or "off" and "on" positions of the switch, according to the position of the contactor arms 55 at the start of the actuations of the pushbutton.

The rearwardly and upwardly inclined ratchet pawl 59 has its forward end in a slot 60a formed in the rear end of the pushbutton 20 and secured in a horizontal transversely extending pivot 61, and a spring wire 62 having one end socketed in the material of the pushbutton as indicated at 63 and its other end socketed in the pivoted end of the pawl as shown at 64, is tensioned to hold the nose of the pawl engaged with the teeth of the ratchet wheel 45. In operation, whenever the pushbutton 20 is pushed inwardly or rearwardly from the position shown in Figure 2, the ratchet wheel will be pushed one-eighth of a revolution by the pawl 59, and when the button is released the retracting spring 39 will push

the button forwardly to its rest or initial position, during which movement the nose of the pawl 59 will be dragged over the periphery of the ratchet wheel to engage the next tooth thereof in readiness for the next actuation of the switch.

The indentations 43 on the ratchet wheel 45 are so placed with relation to the contactor arms 55 that after each actuation of the ratchet wheel the same will be positively held in the position achieved until the next actuation of the ratchet wheel.

Various modifications and changes are contemplated and may obviously be resorted to, without departing from the spirit or scope of the invention as hereinafter defined by the appended claims.

I claim as my invention:

1. A pushbutton switch wherein successive actuation of the pushbutton produces alternate "on" and "off" or "off" and "on" positions thereof, said switch comprising a switch body having a pair of diametrically aligned contacts, an insulated rotary contactor mounted on said body 20 with its axis of rotation between said contacts, said contactor comprising a plurality of pairs of diametrically aligned electrically connected arms arranged to bridge said contacts when engaged therewith, said rotary contactor having peripheral ratchet teeth, a pushbutton mounted on said switch body for reciprocation in a plane substantially at right angles to the rotary axis of said rotary contactor, return spring means for returning said pushbutton to initial inoperative position when released from a pushed-in operative position, and a ratchet pawl operable into effective engagement with said ratchet teeth to turn said contactor a distance of one ratchet tooth on each reciprocation of said pushbutton, 30 whereby a pair of said diametrically aligned arms are caused to alternately engage with and disengage from said pair of contacts, a peripheral portion of said rotary contactor being formed with circumferentially spaced indentations corresponding in spacing to said pairs of contactor arms and the spacer between adjacent pairs of contactor arms, and spring pressed detent means on said body engageable in said indentations to hold said rotary contactor in the positions into 50 which it is operated by the actuation of said pushbutton.

2. A switch comprising a body of insulation formed with a bore leading from its front end and a chamber at the inner end of the bore, a disk of insulation in said chamber having stub shafts extending from opposite sides at its center and rotatably mounted in sockets at opposite sides of the chamber, terminal contacts mounted through a side portion of said body and having outer ends adapted for connection of conductor wires therewith and their inner ends exposed through a side wall of the chamber and spaced from opposite sides of the adjoining stub shaft, a movable contact consisting of a ring of conductive metal mounted against the confronting side face of said disk and having radially extending arms movable into and out of engagement with inner ends of the terminal contacts during step by step rotation of the disk, a ratchet wheel carried by said disk at the opposite side thereof from the movable contact and having teeth about its periphery, certain of the teeth being opposite the arms of the movable contact and other teeth being located between the arms of the said movable contact, a pushbutton slidable longitudinally

through said bore and having a pocket in its inner end, a pawl pivotally mounted in said pocket and projecting from the inner end of the button and yieldably held in engagement with the teeth of said sprocket wheel for imparting turning movement to the disk when the pushbutton is shifted inwardly, and a spring urging the pushbutton forwardly to its normal position.

3. A switch comprising a body formed of longitudinally extending sections secured together and having inner faces formed with registering recesses defining a bore leading from the front end of the body and a chamber at the inner end of the bore, there being an annular pocket intermediate the length of the bore, a disk in said chamber rotatably mounted, terminal contacts mounted through one section of said body and having inner ends exposed through one side wall of the chamber and located in spaced relation to each other diametrically of the disk, screws threaded into the terminal contacts through outer ends thereof for connecting conductor wires with the said contacts, a movable contact mounted against the confronting side of said disk and having arms extending radially of the disk in position for moving into and out of engagement with the terminal contacts during step by step

rotation of the disk, a ratchet wheel carried by said disk and having teeth about its periphery, a bushbutton slideable longitudinally through said bore and having a collar fitting into the annular pocket for limiting sliding movement of the button, a pawl pivoted at the inner end of said button and extending into the chamber with its free end engaging the teeth of said ratchet wheel, a spring in said pocket engaging said collar and urging the button forwardly to an extended position, and a latch yieldably resisting turning movement of the disk.
